UNITED STATES PATENT OFFICE.

WILLIAM RAEURN, OF WATERBURY, CONNECTICUT, ASSIGNOR TO THE MATTATUCK MANUFACTURING COMPANY, OF WATERBURY, CONNECTICUT, A CORPORATION OF CONNECTICUT.

FURNACE REGULATOR.

Application filed January 3, 1924. Serial No. 684,160.

To all whom it may concern:

Be it known that I, WILLIAM RAEURN, a citizen of the United States, residing at Waterbury, county of New Haven, State of Connecticut, have invented certain new and useful Improvements in Furnace Regulators, of which the following is a full, clear and exact description.

My invention relates to furnace regulators and has for its object to produce a new and improved actuating device. It further has for its object to produce a furnace regulating device having stationary and movable means for supporting and adjusting the chain, the stationary part assisting in holding the chain in adjusted position.

The following is a description of my invention reference being had to the accompanying drawings, in which,

20 Figure 1 is a front elevation of a furnace regulator embodying my invention;

Fig. 2 is a side elevation of the same;

Fig. 3 is a rear elevation with a portion of the stationary member broken away; and

25 Fig. 4 is a section on the broken line 4—4, Fig. 1.

Referring more particularly to the drawings 2 is the base member of the regulator having perforated ears 4 for securing the same in position. This base is struck up from sheet metal so as to have a re-entrant portion 6, the periphery 8 of which forms a drum whose surface is at right angles to the flange 10 from which the ears 4 extend.

35 12—12' are two portions extending from the upper part of the periphery of the flange 10 and integral therewith. These portions have at their lower portions outturned ends 14 so as not to catch the regulator chain

40 16. 18 is a movable sheet metal indicating actuating member secured to the base portion by a pivot-post 20 which is surrounded by the flat sheet metal spring 22, the ends of which are held against the inner face of

45 the re-entrant portion of the base by a cotter pin 24. The spring 22 acts to hold the portion 26 of the inner face of the indicating member in frictional engagement with the outer face of the base and tends

50 to thus hold the indicating member in any position in which it may be adjusted. The indicating member is provided with an integral hook 28 upon which is hooked one of the links of the chain 16. It is also provided with integral lugs 30, one of which

engages with one of the stops 34, formed integral with the base, when the indicating member is turned to one or the other of its extreme positions. The chain 16 is moved in one position or the other by turning the indicating member 18, sliding around on the drum 8. In order that the indicating member may be more easily grasped for turning, portions thereof may be cut out and turned up as shown at 36—36, affording convenient thumb and finger pieces.

In order to indicate the effect which may be expected from turning the indicator, I provide the indicator with three openings 38, 40 and 42, spaced apart 120°, and form upon the base portion legends such as "Open," "Closed," "Check" which are so situated as to appear simultaneously beneath the respective openings. The intermediate opening corresponding to the radius at which the hook 28 is located is provided with an index finger 44, which points at the legend describing the resulting action upon the furnace. Thus the parts, as shown in Fig. 1 of the regulator, are set 75 for checking the furnace. If the indicator is moved 120° counter-clockwise the drafts would be closed and if moved from thence 120° counter-clockwise the drafts would be open, provided the chains are connected to 80 the furnace in the usual manner.

The contact of the chain 16 with the drum-like periphery 8 of the stationary member is a very important feature in my invention and necessary for the attaining 90 of its most important object, for the reason that it co-acts to a large extent with the frictional surface 26 and renders the action of the regulator more certain and positive. It further makes it possible to use a much 95 lighter spring 22 on account of its peculiar action. Thus when the indicator is in the position shown in Fig. 1, the weight of the left-hand portion of the chain 16 holds the portion of the chain extending from the hook 28 about two-thirds around the drum counter-clockwise in contact with the drum. This engagement is a frictional engagement 100 and acts as a brake, assisting and holding the indicator in the position in which it is set. A similar result takes place when the index 44 points to the word "Open." When the index points to the word "Closed" the braking effect is divided between the two 105 chains. There is therefore, always the 110

braking effect between the chain and the drum-like portion of the base.

Not only does my regulator have the novel and useful braking action above described, but except for the chain 16, rivet 20 and pin 24 it is made out of sheet metal, there being in addition simply three sheet metal parts.

As will be evident to those skilled in the art, my invention permits of various modifications without departing from the spirit thereof or the scope of the appended claims.

What I claim is:

1. In a device of the character described the combination of a base member having a stationary drum-like forwardly projecting portion, a rotatable actuating member mounted thereon, a pivot connecting said two members, a chain connected to said actuating member and bearing on said projecting drum-like portion so as to make frictional engagement therewith.

2. In a device of the character described the combination of a base member having a stationary drum-like forwardly projecting portion, a rotatable actuating member mounted thereon, a pivot connecting said two members, a chain connected to said actuating member and bearing on said projecting drum-like portion so as to make frictional engagement therewith, and a spring acting upon said pivot and holding said actuating member and base member in frictional engagement.

3. In a device of the character described the combination of a base member having a stationary drum-like forwardly projecting portion, a rotatable actuating member mounted thereon, a pivot connecting said

two members, a chain connected to said actuating member and bearing on said projecting drum-like portion so as to make frictional engagement therewith, said base and actuating members having one a dial and the other an index cooperating with said dial. 40 45

4. In a device of the character described the combination of a base member having a stationary drum-like forwardly projecting portion, a rotatable actuating member mounted thereon, a pivot connecting said two members, a chain connected to said actuating member and bearing on said projecting drum-like portion so as to make frictional engagement therewith, and a spring acting upon said pivot and holding said actuating member and base member in frictional engagement, said base member having a dial and said actuating member having openings disclosing the markings on said dial, and an index cooperating with said dial. 50 55 60

5. In a device of the character described the combination of a base member having a stationary drum-like forwardly projecting portion, a rotatable actuating member mounted thereon, a pivot connecting said two members, a chain connected to said actuating member and bearing on said projecting drum-like portion so as to make frictional engagement therewith, said base and actuating members having one a dial and the other an index cooperating with said dial, said base and actuating members having stops for limiting the movement of said actuating member, and said actuating member having integral thumb and finger pieces. 65 70 75

WILLIAM RAEURN.
